MARLAND FANKBONER, OF CHICAGO, ILLINOIS, ASSIGNOR TO THE GOSS PRINTING PRESS CO., OF CHICAGO, ILLINOIS, A CORPORATION OF ILLINOIS

PROCESS OF PRODUCING BALANCED ROLLS AND THE LIKE

Application filed January 13, 1930. Serial No. 420,320.

My invention relates to a new and improved process of producing balanced rolls and the like. In the manufacture of rolls for use in connection with printing presses, it has been customary to employ a piece of metal pipe for giving the necessary strength and stiffness to the roll, such pipe being mounted in position for rotation by means of trunnions formed in substantially centered position on the outer faces of plugs which are forced into the opposite ends of the pipe in alignment with each other. With the pipe thus substantially centered about an axis of rotation, it has been possible to cast or otherwise form the body of the roll on the pipe, and to turn down the outer face of such body if necessary for obtaining the required true cylindrical form in concentric position about the axis of the pipe, any necessary balancing being done after the operation of truing the surface.

There are, however, in practice several disadvantages with respect to this process. In the first place, it is desirable that the rolls be handled no more than is absolutely necessary after the application of the body material to the pipe or other supporting bar, and particularly after the truing of the body to cylindrical form. It will be understood that such rolls are in many cases comparatively heavy and are always liable to injury in handling even to the necessary extent. In the second place, it is desirable in many cases that the mechanical work on the roll involving any turning or other machine work on the metal portion of the roll be done in its entirety before the rubber or other composition body material is applied, making it unnecessary that the rolls be returned to the metal working shop or department after the application of the body material. This is particularly important in cases where the metal portions of the rolls are produced by one concern and the body material is applied by a different concern.

It has been the object of my invention to provide a new and improved process of producing balanced rolls and the like, by the use of which I may avoid the necessity for balancing the roll after the application of

the rubber composition or other body material to the metal support, and also by the use of which I may be enabled to complete all of the machine work on the roll involving the cutting of metal before the body material is placed in position.

It is one of the objects of my invention to effect this result by the use of steps which can be very quickly and very readily carried out without unduly increasing the cost and without materially complicating the procedure. It is another object of my invention to improve the method of producing balanced rolls and the like in sundry details hereinafter pointed out. The preferred procedure by which I have accomplished my objects is set forth in the following specification, reference being made to the accompanying drawings for illustration thereof. That which I believe to be new is set forth in the claims.

In the drawings,—

Fig. 1 is a longitudinal central section through the supporting member of a roll at a preliminary stage of the production of the roll by my improved process;

Fig. 2 is a longitudinal central section showing the addition of a layer of material to the support;

Fig. 3 is a view showing the same parts as are illustrated in Fig. 2 but with the roll trued into concentric form about the axis of rotation and with the roll as a whole balanced with respect to said axis;

Fig. 4 is a side view of one end portion of a completed roll, broken away at the end to show the body material in section; and

Fig. 5 is a side view of one end portion of a completed roll of slightly different construction, also broken away at the end for better showing the construction.

Referring now to Figs. 1 to 4 inclusive, 10 indicates a rough piece of metal pipe having plugs 11 mounted in its ends, each of said plugs having a shaft or trunnion 12 formed on its outer face in such position thereon that the two shafts 12 are in approximate alignment with each other and the pipe is in approximately centered position with respect to the axis of said shafts. 100

The production of a support comprising bearings about which the member is approximately centered constitutes the first step of my improved process. I prefer to 5 produce the support by the use of a pipe as illustrated, but my invention broadly is not limited to this particular form. Ordinarily such support will not be found to be balanced about the axis of the shafts, 10 since there is no necessity for precise accuracy in the production of this part. Accuracy of balance at this stage would not, however, be objectionable. In the drawings, the shafts 12 are shown slightly out of center 15 with respect to the plugs 11, as exemplifying the lack of necessity for accuracy, the inaccuracy being exaggerated in the drawing as compared with ordinary results in practice. Indeed, the plugs with their centered shafts would ordinarily be fairly accurate, there being much more likelihood of inaccuracy in balance in the pipe than in the plug mountings for the pipe.

With the support 10 roughly centered 25 about an established axis of rotation, a layer 13 of material which can be readily applied and easily machined is placed in position upon the support completely surrounding it at its sides. This layer 13 may be applied by any suitable process available by 30 which it is made to fit snugly on the support at every point so as to fill up any possible irregularities in the outer face of the support. In the embodiment of my invention 35 as shown in Fig. 2, the layer 13 is applied in the form of a plastic mixture, being plastered on roughly and permitted to harden and dry in position, such material being of substantially the same weight as that of the rubber or composition which is 40 to form the body of my completed roll. I have found that in case rubber is to be used for the body of the roll, the layer 13 may to advantage be formed of water putty. All 45 that is required with respect to the layer 13 in the form of the invention as shown in Fig. 3 is that such layer when hardened may hold its form, may have a tight fit at all points on the support, may be easily 50 machined on its surface, and may be of substantially the same weight as that of the body of the roll later to be applied.

After the application and drying of the 55 layer 13, if the outer face of such layer is not already in concentric form about the axis of the shafts 12, as shown in Fig. 3, in such case said layer is turned down into such concentric form. The roll in such condition is then balanced dynamically about the axis 60 of the shafts 12. In the form of device as shown in said Fig. 3, the balanced effect has been produced by boring out the metal at one side of the plug 11 at one or more points as indicated at 14. This particular manner 65 of balancing is not a requisite, however, any

suitable method of balancing being satisfactory which embodies the correction in or in connection with the metal support as distinguished from a correction in or in connection with the layer 13.

These supports in the condition as shown in Fig. 3 are ready for shipment to the shop or department in which the body material is to be applied to the supports. Inasmuch as the layer 13 of putty or other suitable material is to be removed in any event before the application of the body material, there is no necessity for any undue care with respect to the handling of the parts.

For completing the roll after the balancing operation, all portions of the layer 13 are removed from the support, and the body 15 of rubber or composition of the desired character is cast or otherwise applied to the support in the ordinary manner, care being taken that the body material fit snugly at all points about the support 10, the ordinary steps being taken for insuring that the body shall have the necessary tight anchorage to the support. In case the material of the body 15 is cast in precisely concentric form about the axis of the shafts 12, the resulting roll will be found to be perfectly balanced without the necessity for any further steps, the accuracy of this result depending, of course, upon the accuracy with which the weight of the material of the layer 13 when dried and hardened matches the weight of the material of the body 15 in its finished form. If desired, the body 15 may be initially formed oversize, as is usually done when the body is formed of rubber, and may then be turned down into concentric form with respect to the axis of the shafts 12, such layer of rubber being first preferably vulcanized. If the process has been followed with close attention to all the refinements as above set forth, the turned down roll will be found to be in 100 dynamically balanced condition with respect to the axis of the roll.

In Fig. 5 I have shown a slightly different form of structure. In this form, a rough metal pipe 16 provided with plugs 17 having trunnions 18 on their faces is provided with a layer 19 of Babbitt metal or the like, preferably by being cast in position thereon, the outer face of which layer is very readily turned down into concentric form with respect to the axis of the trunnions. After the layer 19 is brought to its concentric form with respect to the axis of the roll, the roll is balanced in any approved manner, whereupon it is ready for shipment to the shop or department by which the composition body is to be applied. In this case, a rubber composition body 20 is applied directly to the soft metal layer 19, this soft metal layer having sufficient strength when sup- 130

ported directly by the support 16 to hold the body firmly in fixed position on the support, even though such layer of soft metal has very little strength in and of itself.

5 By the use of a soft metal for the layer of material to be applied before the turning and balancing operations, the necessity for care with respect to the weight of such material in comparison with the weight of the material of the body 20 is eliminated, since such layer 19 is to be left in position upon the support. By reason of the use of soft metal, the turning operation may be carried out rapidly and with a slight expenditure of 15 power.

After the application of the layer of body material 20, the outer face of this layer must, of course, be dressed down into concentric form with respect to the axis of the roll, 20 unless such layer 20 has been cast or otherwise applied in precisely concentric form about the axis. When the layer 20 is brought to its concentric form, the roll will be found to be in dynamically balanced condition, 25 since the same amount of the body material is added at opposite sides of the axis at every point throughout the length of the roll.

While I prefer to employ the process as above described, it is to be understood that 20 I do not limit my invention precisely to the procedure as outlined, except so far as the claims may be so limited by the prior art.

I claim:

1. The process of producing balanced rolls 35 and the like, comprising the provision about a metal support of a layer of easily applied material with its outer surface concentric with respect to an established axis of rotation of said support, then balancing said covered support with respect to said axis, and then after the balancing operation providing a layer of body material about said metal support with its outer surface concentric with respect to said axis.

45 2. The process of producing balanced rolls and the like, comprising the provision about a metal support of a layer of easily applied material with its outer surface concentric with respect to an established axis of rotation of said support, then balancing said covered support with respect to said axis, then after the balancing operation removing said layer from the support, and then providing a layer of body material about said support 50 with its outer surface concentric with respect to said axis.

55 3. The process of producing balanced rolls and the like, comprising the provision about a metal support of a layer of easily applied material with its outer surface concentric with respect to an established axis of rotation of said support, then balancing said covered support with respect to said axis, then after the balancing operation removing 60 said layer from the support, and then pro-

viding about said support a layer of body material of substantially the same weight as that of the material of said first named layer with the outer surface of said second layer concentric with respect to said axis.

70

4. The process of producing balanced rolls and the like, comprising the provision of a layer of easily applied and easily machined material about a metal support, then turning said layer down serving to make its outer surface concentric with respect to an established axis of rotation of said support, then balancing said covered support with respect to said axis, and then after the balancing operation providing a layer of body material about said metal support with its outer surface concentric with respect to said axis.

75

5. The process of producing balanced rolls and the like, comprising the provision of a layer of easily applied and easily machined material about a metal support, then turning said layer down serving to make its outer surface concentric with respect to an established axis of rotation of said support, then balancing said covered support with respect to said axis, then after the balancing operation removing said layer from the support, and then providing about said support a layer of body material of substantially the same weight as that of the material of said first named layer with the outer surface of said second layer concentric with respect to said axis.

80

6. The process of producing balanced rolls and the like, comprising the provision about a metal support of a layer of material of substantially the same weight as that of the rubber composition to be used for the body of said finished roll with its outer surface concentric with respect to an established axis of rotation of said support, then balancing said covered support with respect to said axis, then after the balancing operation removing said layer from the support, and then providing a layer of said rubber composition about said support with its outer surface concentric with respect to said axis.

95

7. The process of producing balanced rolls and the like, comprising the provision about a metal support of a layer of material of substantially the same weight as that of the rubber composition to be used for the body of said finished roll, then turning said layer down serving to make its outer surface concentric with respect to an established axis of rotation of said support, then balancing said covered support with respect to said axis, then after the balancing operation removing said layer from the support, and then providing a layer of said rubber composition about said support with its outer surface concentric with respect to said axis.

105

8. The process of producing balanced rolls and the like, comprising the provision about a metal support of a layer of material of 115

65 90 95 100 105 110 115 120 125 130

- substantially the same weight as that of the rubber composition to be used for the body of said finished roll, then turning said layer down serving to make its outer surface concentric with respect to an established axis of rotation of said support, then balancing said covered support with respect to said axis, then after the balancing operation removing said layer from the support, then providing a layer of said rubber composition about said support, then vulcanizing said rubber composition, and then turning the outer surface of said layer down into concentric form with respect to said axis.
15. The process of producing balanced rolls and the like, comprising the provision about a metal support of a layer of putty with its outer surface concentric with respect to an established axis of rotation of said support, then balancing said covered support with respect to said axis, then removing said layer of putty, and then providing a layer of rubber composition about said support with its outer surface concentric with respect to said axis.
20. The process of producing balanced rolls and the like, comprising the provision of a layer of easily applied material about a metal support in the form of a rough bar having bearings at its ends with the outer surface of said layer concentric with respect to said bearings, then balancing said covered support with respect to the axis of said bearings, and then after the balancing operation providing a layer of body material about said support with its outer surface concentric with respect to said axis.
25. The process of producing balanced rolls and the like, comprising the provision of a layer of easily applied material about a support in the form of a piece of commercial pipe provided at its ends with plugs having bearing shafts on their outer faces with the outer surface of said layer concentric with respect to the axis of said shafts, then balancing said covered support with respect to said axis, and then after the balancing operation providing a layer of body material about said support with its outer surface concentric with respect to said axis.
30. The process of producing balanced rolls and the like, comprising the application about a metal support of a layer of plastic material adapted to harden in place and bringing said layer to concentric form about an established axis of rotation of the support, then balancing said covered support with respect to said axis, and then after the balancing operation providing a layer of body material about said support with its outer surface in concentric form with respect to said axis.
35. The process of producing balanced rolls and the like, comprising the application about a metal support of a layer of Babbitt metal about a metal support of a layer of

plastic material adapted to harden in place, then after the hardening of said material dressing down the outer surface of the layer into concentric form about an established axis of rotation of the support, then balancing said covered support with respect to said axis, and then after the balancing operation providing a layer of body material about said metal support with its outer surface in concentric form with respect to said axis.

14. The process of producing balanced rolls and the like, comprising the application about a metal support of a layer of plastic material adapted to harden in place and adapted when hardened and dried to weigh substantially the same as the material to be used for the body of the roll and bringing said layer to concentric form about an established axis of rotation of said support, then balancing said covered support with respect to said axis, then removing said layer from said support, and then providing a layer of said body material about said support with its outer surface in concentric form with respect to said axis.

15. The process of producing balanced rolls and the like, comprising the provision of a layer of putty about a support in the form of a piece of commercial pipe provided at its ends with plugs having bearing shafts on their outer faces, then after the hardening of said putty dressing down the surface into concentric form about the axis of said shafts, then balancing said covered support with respect to said axis, then removing said layer from said support, then providing a layer of rubber composition about said support, and then dressing down the surface of said second named layer into concentric form about said axis.

16. The process of producing balanced rolls and the like, comprising the provision about a metal support of a layer of easily applied material with its outer surface concentric with respect to an established axis of rotation of said support, then balancing said covered support with respect to said axis, and then providing a layer of body material about said first named layer with its outer surface concentric with respect to said axis.

17. The process of producing balanced rolls and the like, comprising the provision about a metal support of a layer of soft metal with its outer surface concentric with respect to an established axis of rotation of said support, then balancing said covered support with respect to said axis, and then providing a layer of body material about said first named layer with its outer surface concentric with respect to said axis.

18. The process of producing balanced rolls and the like, comprising casting a layer of Babbitt metal about a metal support,

turning said layer down into concentric form about an established axis of rotation of said support, then balancing said covered support with respect to said axis, and 5 then providing a layer of body material about said layer of Babbitt metal with its outer surface concentric with respect to said axis.

19. The process of producing balanced 10 rolls and the like, comprising casting a layer of soft metal about a rough metal support, turning said layer down into concentric form about an established axis of rotation of said support, then balancing said covered 15 support with respect to said axis, then providing a layer of rubber composition about said layer of soft metal, and then turning said last named layer of material down into concentric form about said axis.
